UNITED STATES PATENT OFFICE.

MERRICK A. MIHILLS, OF PAINESVILLE, OHIO.

BARBED FENCE.

SPECIFICATION forming part of Letters Patent No. 269,444, dated December 19, 1882.

Application filed July 17, 1882. (No model.)

To all whom it may concern:

Be it known that I, MERRICK A. MIHILLS, of Painesville, in the county of Lake and State of Ohio, have invented certain new and useful 5 improvements in Barbed Fences; and I do hereby declare that the following is a full, clear, and exact description of the invention, which will enable others skilled in the art to which it appertains to make and use the same, 10 reference being had to the accompanying drawings, which form a part of this specification, and in which—

Figure 1 is a perspective view of a piece of twisted fence-wire provided with one of my revolving bars or spurs. Fig. 2 is a side view 15 of a section of wire, showing three of the revolving spurs; and Fig. 3 is a cross-section through one of the spurs with its bearing-plate and holding-wires.

20 Similar letters of reference indicate corresponding parts in all the figures.

My invention has relation to barbed-wire fences; and the novelty consists in the construction and arrangement of parts, as will be 25 more fully hereinafter set forth, and specifically set forth in the claim.

In the accompanying drawings, the letter A represents a twisted two-strand fence-wire. At suitable distances apart are inserted between 30 the strands of the wire lozenge-shaped plates B, having grooved edges b, and a central longitudinal slot, a, for the insertion of the revolving spur-wheel or rowel C, the plates being held in place by the strands of the wire, 35 passing through the grooves or channels b, as

shown more clearly in Fig. 3 of the drawings. In twisting the wire the strands will bind firmly in their respective grooves, so as to hold the plates properly in place at all times.

The advantages of my barbed fence-wire will 40 readily be appreciated by all who have had experience with barbed fences. When stock runs against the rotary bars or rowels, these, while inflicting a certain degree of punishment sufficient for the purpose, will give or yield and 45 not lacerate or cut the flesh of the animal, as in the case of stationary or rigid bars, the cruelty of which has caused their use to be prohibited in several of the States.

I am aware of Patent No. 230,445, of 1880, 50 and the construction therein set forth is not sought to be covered in this application.

Having thus described my invention, I claim and desire to secure by Letters Patent of the United States—

The barbed fence-wire composed of the twisted strands A, lozenge-shaped plates B, slotted at a and having grooved edges b, and spur-wheels or rowels C, journaled in the slotted plates, constructed and combined substantially 60 as and for the purpose herein shown and described.

In testimony that I claim the foregoing as my own I have hereunto affixed my signature in presence of two witnesses.

MERRICK A. MIHILLS.
